HIGH SPEED TELEPICTURE SYSTEM

William G. H. Finch, New York, N. Y.

Application March 9, 1936, Serial No. 67,938

12 Claims. (Cl. 176—7)

This invention relates to telepicture systems and, more particularly, relates to high speed telepicture communication by electronic scanning.

In the conversion of pictures or messages to electrical telepicture signals, prior systems employed mechanical scanning operations whereby a narrow beam of light was traced over the picture elements and corresponding variations in the light beam intensity were converted to telepicture signals by photoelectric means. In some systems the picture record was mounted upon a drum; in other systems the picture sheet was successively advanced past an oscillating scanning means which moved transversely with respect to the sheet whereby successive transverse scanning operations were perfected. Corresponding scanning operations were produced at the receiving station in synchronism with the transmitter scanner for composing a telepicture reproduction.

The speed of operation of prior telepicture systems was limited by the mechanical scanning operations and the requirements for maintaining the transmitter and receiver scanning mechanism in perfect phase synchronization. The inertia of the moving mechanical components and the mechanical synchronizing operations have limited these systems to speeds of the order of 100 to 150 lines per minute for quality reproduction. I contemplate eliminating substantially all of the mechanical scanning and synchronizing elements in a telepicture system, which permits much higher transmission speeds.

In carrying out my present invention, a cathode ray tube is used to generate a scanning beam which is focused upon a picture film. The beam is caused to oscillate across the film so as to successively traverse the picture elements whereby a photoelectric cell may be actuated. The film is automatically advanced by an amount equal to the width of a scanning line at the end of each scanning operation. A synchronizing impulse is simultaneously generated for advancing a corresponding receiving film at a remote station. Each successive line of the receiving film is exposed to a cathode ray image of the telepicture signals from the transmitting station in a manner to be described in detail hereinafter. A telepicture reproduction is had with either a half tone or continuous tone shading as will be set forth.

Accordingly, an object of my invention is to provide a novel telepicture system.

Another object of my invention is to provide a novel telepicture system utilizing electronic scanning and synchronization operations.

Still another object of my invention is to pro-

vide a novel electronic high speed telepicture system.

A further object of my invention is to provide a novel continuous high speed telepicture system.

These and other objects of my invention will become apparent in the following description in connection with the drawings in which:

Figure 1 is a schematic illustration of a preferred embodiment of an electronically scanned telepicture system in accordance with my present invention.

Figure 2 is a characteristic curve of the linear sweep oscillator voltage output.

Figure 3 is a schematic representation of the scanning operation of the picture film during transmission.

Figure 4 is a perspective illustration of a preferred photoelectric tube for translating the scanning beam picture impulses to corresponding telepicture signals.

Figure 5 is a graphical illustration of a typical telepicture signal for a single line of scanning.

Figure 6 is a schematic diagram of an electronically scanned receiving telepicture system for translating the telepicture signals of the transmitter in Figure 1.

Figure 7 is a representation of the scanning operation during the reception of the telepicture signals.

Figure 8 is a diagrammatic representation of a preferred light filter or screen at the telepicture receiver.

Referring to Figure 1, the cathode ray tube 10 generates an electron beam 11 which is caused to traverse a fluorescent screen 12 at one end 35 of the tube 10. The generation of the electron beam 11 is familiar to those skilled in the electronic art and is diagrammatically illustrated. The cathode 13 is heated by the heater 14 which is connected to a suitable battery supply, not shown. 40 The first anode 15 concentrates the emitted electrons into an electron beam. The high voltage anode 16 accelerates the electrons of the beam 11 which passes between the electrostatic deflecting plates 17—18 and 19—20, to the fluorescent screen 12. A high voltage direct current potential source 21 supplies the operating potentials for the electrodes of the cathode ray tube 10. A potentiometer 22 is connected across the battery 21. The high voltage anode 16 is connected 50 to the positive end of the potentiometer 22, which end is also connected to ground potential in my preferred embodiment. The first anode 15 is connected to a suitable intermediate positive potential by variable contact 23. The control grid 55

25 is suitable negatively biased by tap 24 on the potentiometer 22. Deflecting plates 17 and 19 are directly connected to ground potential and accordingly assume the same potential as anode 5 16. Deflecting plate 18 is directly connected to ground. The deflecting plate 20 is connected to ground through a high resistance 26. All the deflecting plates 17 to 20 accordingly have a common static potential which is at ground potential, 10 an operating expedient commonly employed.

The output of a linear sweep oscillator 27 is connected to deflecting plate 20 by a connection lead 28. The deflecting plates 19 and 20 deflect the electron beam 11 horizontally; the vertical 15 deflecting plates 17-18 are both at ground potential and are ineffective in deflecting the beam. The linear sweep oscillator 27 causes the electron beam 11 to periodically sweep horizontally across the fluorescent screen 12. Figure 2 is the linear 20 sweep characteristic curve illustrating how the voltage applied between deflecting plates 19 and 20 varies with time. The linearly rising portion 30 of the curve corresponds to the constant rate at which the beam 11 is transversely moved 25 across screen 12. The return portion 31 of the curve corresponds to the rapid return of the beam to the opposite end of the screen 11 after the completion of its periodic traverse. The time interval represented by intercepts a-b of 30 Figure 2 corresponds to the time in which beam 11 is uniformly swept horizontally across the fluorescent screen 12. The shorter time intercept b-c represents the rapid return interval of 35 the beam for its periodic excursion.

35 The electron beam 11 produces a spot of light upon the fluorescent screen 12. The light beam 32 generated at the fluorescent screen 12 is used as a scanning light beam for the picture film 33 to be transmitted. The light beam 32 is focused 40 by a lens system 34 upon a narrow portion or line segment of the film 33. The film 33 alters the intensity of the light beam 32 passing thru it according to the shading of the picture elements being transmitted. A photoelectric cell 45 35 intercepts the beam 32 and generates electrical signals varying in accordance with the elemental shading of the film 33.

Figure 3 is a schematic illustration of the manner in which the electronic scanning is performed 50 in accordance with my present invention. The film 33 is somewhat narrower than the diameter of the face 12 of the cathode ray tube 10. Dashed line 11a represents the excursion, transverse to the film 33, of the electron beam 11 across the 55 fluorescent screen 12. It will be understood that the trace of the electron beam 11a upon the fluorescent screen 12 will be visually evidenced as a brilliant line of light. The excursion a'-b' of the path 11a from right to left, corresponds 60 to the time interval a-b of Figure 2. The return sweep represented by the time interval b-c corresponds to the return sweep b'-a', from right to left of the beam 11a. The portion a'-c' of the beam 11a corresponds to the electronic 65 scanning period for the picture film 33. The portion c'-b' of beam 11a corresponds to the synchronizing period to be hereinafter described in detail.

The fluorescent screen 12 is designed to have a 70 low persistence so that the excursion of the electron beam across the path 11a will not produce a continuous line of light but rather a moving point so that the beam of light 32 projecting through the film 33 will correspond to the 75 elemental shading of the picture intercepted by the

path of the beam. The moving spot of light should be brilliant and it need not have a small diameter. The focusing lens system 34 reduces the diameter of the brilliant scanning spot to a diameter equal to the width of the scanning line traversing the film 33. If the transmitted pictures are to be scanned with a detail corresponding to 100 lines per inch, then the diameter of the focused scanning point upon film 33 will correspondingly be one-hundredth of an inch. It is important that the persistence of the fluorescent screen 12 be low so that an effective moving scanning point or beam 32 is projected through film 33 to insure the generation of telepicture signals in accordance with the elemental shading 15 of the picture.

The photoelectric tube 35 which I prefer to employ is illustrated in Figure 4. Tube 35 comprises two photo-sensitive cathodes 36 and 37. The cathode 36 responds to the light beam projecting through the film 33 corresponding to the portion a'-c' of Figure 3 and represented thereon by the dotted section 36. The photo-sensitive cathode 37 is shorter in length and is represented by the dotted section 37 in Figure 3 25 and corresponds in length to the portion c'-d' of the light beam 11a. Photoelectric tube 35 has a common anode 38.

The telepicture signals generated between the electrodes 36-38 of tube 35 are conducted to an 30 amplifier and modulator stage 40 by leads 41-42 (Figure 1). An audio frequency oscillator 43 is impressed upon amplifier-modulator stage 40 by leads 44-45. The frequency of oscillator 43 may for example be 3000 cycles. The type of modulator at stage 40 which I prefer to employ is commonly termed screen grid modulation. As will be understood by those skilled in the art, signals at the output 46-47 of stage 40 will be at a minimum intensity when a dark picture segment is 40 being transmitted and a large signal intensity will correspond to a light picture segment. Figure 5 is a graphical representation of a typical signal which may be produced at the output 46-47 of stage 40. The time interval a''-c'' of Figure 5 represents one scanned line of the picture on film 33. The ordinate E is the relative voltage intensity of the telepicture signal.

The alternating current curve 50 represents the 50 audio frequency carrier of the signal, namely 3000 cycles. Figure 5 is a schematic illustration and is accordingly not drawn to scale. The envelope 51 of the carrier 50 represents the telepicture modulations superimposed upon the audio carrier 50. The envelope 51 is symmetrical with respect 55 to the horizontal axis as will be evident to those skilled in the art. The maximum intensity represented by 52-52 corresponds to a white picture element; the zero intensity 53 corresponds to a black picture element. Intermediate picture 60 shadings produce intermediate amplitudes.

The output 46-47 of stage 40 may be transmitted to a remote receiving stage along wire lines or by radio transmission. In Figure 1, I illustrate a radio transmission system for the telepicture 65 signals. The signals are impressed upon a radio frequency modulator stage 54 by leads 46-47. A radio frequency oscillator 55 produces a carrier wave which is modulated by the audio frequency telepicture signals in stage 54. The radio frequency transmitter 56 amplifies the signals from modulator stage 54 for transmission by antenna 57.

It is to be understood that the continuous record film 33 is stationary during the scanning 75

operation and is periodically advanced past the scanning beam 32 in a predetermined manner. The film 33 is contained in a roll 60 and is automatically advanced by the stepping mechanism 61 upon the take-up roll 62. For a scanning operation of 100 lines per inch, the stepping mechanism 61 moves film 33 past beam 32 one-one hundredth of an inch at the completion of each scanning operation. When the scanning beam 10 moves to the segment $c'-d'$ (Figure 3) the beam 32 will impinge upon the photo-sensitive cathode 37 and produce a signal in the form of an impulse upon amplifier 63 through leads 64-65. The output 66-67 of amplifier 63 is connected to the 15 automatic advancing mechanism schematically represented at 61. Mechanism 61 may for example be well known electro-magnetic periodic advancing means which is actuated by the electrical impulses produced at the end of each 20 scanning excursion 11a of the electron beam 11 as will be understood. The film 33 is accordingly advanced the proper amount during this interval so that the adjacent line may be scanned during the next cycle of operation.

25 The signal impulse produced at electrodes 37-38 is also used for the synchronizing impulse at the remote receiving station for automatically advancing the receiving record sheet in a manner to be described. This impulse is accordingly impressed upon the amplifier-modulator stage 40 by means of a unidirectional impedance device 70 connected between leads 65 and 41 and conductive in the direction towards the amplifier stage 40. The unidirectional impedance 70 may be a 30 buffer stage of thermionic amplification or a rectifier. A unidirectional impedance is used to prevent the picture signals generated at electrodes 36-38 from being impressed upon the amplifier 63. The magnitude of the impulse impressed 35 upon amplifier 40 is greater than that of any corresponding telepicture signals so that the receiving station may selectively respond to this signal for operating the automatic film advancing mechanism.

40 Figure 6 is a schematic representation of the electronic telepicture receiving system to be used for translating the telepicture signals radiated from the transmitter of Figure 1 by the antenna 56. The radio receiver 71 amplifies the radio 45 frequency signals impressed upon its antenna 72 and rectifies the modulated radio frequency carrier signals. The output 73-74 of receiver 71 corresponds in signal wave form to that at the output 46-47 of amplifier-modulator stage 40 50 of the transmitter. The output 73-74 is the audio carrier modulated in accordance with the picture shading being transmitted, corresponding for example, to its graphical representation in Figure 5. Connection lead 75 impresses the telepicture signals upon vertical deflecting plate 76. The opposite vertical deflecting plate 77 is connected to ground through lead 78. A high resistance 79 connects deflecting plate 76 to electrostatic ground potential. The plates 76-77 are 55 accordingly at a common static potential with respect to the high potential anode 80, namely at ground potential. The receiver cathode ray tube 81 is similar to the corresponding transmitter tube 10. The electrode potential supply is from the 60 potentiometer 82 connected across the high voltage supply 83, the positive terminal of which is connected to ground. The first anode 84 and the control grid 85 are connected to suitable potential 65 points on the potentiometer 82. The electron beam 86 is generated at the cathode 87 and

70 focused upon the fluorescent screen in the well known manner. The horizontal deflecting plates 89-90 are actuated by the linear sweep oscillator 91. The output of sweep oscillator 91 is connected to the horizontal deflecting plate 89 by lead 75 92.

75 The frequency of linear sweep oscillator 91 is adjusted close to that of the frequency of the transmitter sweep oscillator 27. Oscillator 91 is 10 impulse excited by the synchronizing signals so that is will have the exact frequency of the transmitter scanning frequency. The electron beam 86 will accordingly be oscillated horizontally across the center of the fluorescent screen 88 by 15 deflecting plates 89-90. A marginal amplifier 93 is connected to the output 73-74 of the receiver 71 by input leads 94-95. Marginal amplifier 93 is suitably biased so as to respond only to a predetermined amplitude of input signals, 20 namely to the amplitude of the synchronizing signals. Since the synchronizing signals are greater in amplitude than any of the telepicture variations, amplifier 93 will respond only to the synchronizing impulses as will be understood by 25 those skilled in the art. The output 96-97 of marginal amplifier 93 will accordingly be periodically amplified impulses corresponding to the transmitted synchronizing impulses during scanning period $c'-d'$ (Figure 3). The output 96-97 is 30 connected to the linear sweep oscillator 91 by leads 98-99 to provide the frequency synchronization therefor in a well known manner. The horizontal scanning action of electron beam 86 will correspond to that of electron beam 11 at 35 the transmitter. The phase adjustment of beam 86 is automatically provided by proper design of the impulse excited linear sweep oscillator 91 in relation to the predetermined occurrence of the periodic synchronizing impulse at the end of each scanning line.

40 The incidence of electron beam 86 upon fluorescent screen 88 will produce a brilliant spot of light which is suitably focused by lens system 100 upon the receiving film 101. The continuous film 101 is contained upon take-up roll 102 and 45 is automatically stepped past the scanning beam by stepping mechanism 103. Mechanism 103 is similar to the stepping mechanism 61 of the transmitter and is electrically actuated by the amplified synchronizing impulses from the output 96-97 of amplifier 93. Film 101 is advanced in 50 the present example one one-hundredth of an inch at the end of each scanning line operation.

55 Film 101 is placed opposite the fluorescent face 88 of tube 81 in a position corresponding to that of the transmitter represented by Figure 3. Points a' , c' , and b' of Figure 7 correspond to the similarly marked points of Figure 3. The interval $a'-c'$ is equal to the width of the film 101, for example, six inches. The transmitter film 33 60 would also be six inches wide. The interval $c'-b'$ corresponding to the synchronizing impulse period may be one inch in length.

65 The vertical deflecting plates 76-77, actuated by the telepicture signals will superimpose upon the horizontally oscillated electron beam 86, a motion corresponding to the wave form 50 represented in Figure 5. The fluorescent image of the actuated beam 86 will appear upon screen 88 in the form represented by curve 104. The transmitter linear sweep oscillator 27 is electrically 70 coupled to the audio frequency oscillator 43 by connection 68-69. These coupled oscillators are maintained in an integral multiple relation in a manner well known in the art. The frequency 75

of oscillator 43 may be tuned to 3000 cycles and the frequency of the linear sweep oscillator 27 adjusted to, for example, five cycles per second, the frequency ratio in this example being 600 to 1. Due to the multiple relation of the carrier and sweep frequencies, the image 104 will be stationary. The envelope 105 of image 104 corresponds to the picture shading modulation of the audio carrier. The envelope 106 is similar in shape to the transmitted signal envelope 52 represented in Figure 5.

The horizontal axis a'-b' of fluorescent screen 88 is preferably rendered ineffectual or is screened from the receiving film 101. A light image of a zero intensity signal will accordingly not be impressed upon film 101 and a black picture element will result thereon. A white picture element represented by the maximum image width 106-106 corresponds to the signal intensity representation 52-52 in Figure 5. Focusing system 100 is designed to reduce the light image width 106-106 to the width of the scanning line impressed upon film 101, namely one one-hundredth of an inch. Intermediate picture shadings as hereinabove described, will be represented by intermediate light image widths on the fluorescent screen 88. The picture shading recorded on film 101 is proportional to the width of the light image 104 opposite the particular element of the line during scanning thereof.

If the frequency of the picture carrier is relatively high, the image 104 thereof will be represented as a light area having an envelope corresponding to the picture shading modulation. A continuous tone reproduction will accordingly result. On the other hand, if the picture carrier frequency is relatively low, a distinct sinusoidal wave form similar to the illustration 104 will result with a similarly shaped envelope 105. A discrete point by point or half-tone reproduction will result due to the non-contiguous light image. This effect may be increased by shielding the upper or lower half of the light image 104.

The persistence of fluorescent screen 88 should be low enough so that the light image 104 of each successive line scanned will disappear in the interval between scanning impressions, namely, during the synchronizing period a'-b' and the sweep return interval 31 (Figure 2). The important feature of my present invention resides in the representation of the picture shading by a corresponding electronically produced varying width light image which is focused to a narrow scanning light beam upon a sensitive picture film. To compensate for a non-linear picture shading translation, a light filter or screen 107 may be interposed between the signal image 104 and the film 101. Figure 8 illustrates a preferred shading for the light filter or screen 107. The outer portions 108 of screen 107 are transparent. A gradual reduction of light transmission is effected between the outer portions 108 and the central portion 109. The effectiveness of the varying widths of light image 104 on screen 88 upon the film 101 is accordingly predetermined by the light transmission characteristic of the screen 107. In the illustrated screen 107, the portions of the light image 104 on screen 88 furthest away from the horizontal axis a'-b' will be more effective than the portions nearer to axis a'-b' as will be understood. By drawing a narrow opaque line 110 across the center of screen 107, the ineffective fluorescent section a'-b' of screen 88 may be dispensed with so

that a standard cathode ray tube 81 may be utilized.

Although I have described a particular embodiment of a telepicture system utilizing electronic scanning, modifications thereof falling within the spirit and scope of my present invention will be evident to those skilled in the art and I do not intend to be limited except as set forth in the following claims.

1. In a telepicture system, a transmitter comprising an electronic scanner including means for generating an electron beam, and means for oscillating said beam in one direction at a predetermined rate transversely of a picture film to be transmitted with one oscillation for each line of scanning; a photoelectric cell in operative relation with said scanner and said picture for generating telepicture signals of individual lines of scanning in accordance with the shading of said picture as said scanner scans the picture; a source of carrier current; means for modulating said carrier current in accordance with said telepicture signals; and a receiver comprising a corresponding electronic scanner including means for generating an electron beam, means for oscillating said receiver beam in one direction at said predetermined rate with one oscillation corresponding to each of said lines of scanning, and means for simultaneously moving said receiver beam transverse to said oscillating direction in accordance with the received picture modulated carrier current whereby the width along any section of the image is proportional to the degree of picture signal modulation.

2. In a telepicture system, a transmitter comprising an electronic scanner including means for generating an electron beam, and means for oscillating said beam in one direction at a predetermined rate transversely of a picture film to be transmitted with one oscillation for each line of scanning; a photoelectric cell in operative relation with said scanner and said picture for generating telepicture signals of individual lines of scanning in accordance with the shading of said picture as said scanner scans the picture; a source of carrier current; means for modulating said carrier current in accordance with said telepicture signals; and a receiver comprising a corresponding electronic scanner including means for generating an electron beam, means for oscillating said receiver beam in one direction at said predetermined rate with one oscillation corresponding to each of said lines of scanning, and means for simultaneously moving said receiver beam at right angles to said oscillating direction in accordance with the received picture modulated carrier current whereby the width along any section of the image is proportional to the degree of picture signal modulation.

3. In a telepicture system, a transmitter comprising an electronic scanner including means for generating an electron beam, and means for oscillating said beam in one direction at a predetermined rate transversely of a picture film to be transmitted with one oscillation for each line of scanning; a photoelectric cell in operative relation with said scanner and said picture for generating telepicture signals of individual lines of scanning in accordance with the shading of said picture as said scanner scans the picture; a source of carrier current; means for modulating said carrier current in accordance with said telepicture signals; a receiver comprising a cor-

responding electronic scanner including means for generating an electron beam, means for oscillating said receiver beam in one direction at said predetermined rate with one oscillation corresponding to each of said lines of scanning transversely of a light sensitive record sheet, means for simultaneously moving said receiver beam at right angles to said oscillating direction in accordance with the received picture modulated carrier current whereby the width along any section of the image is proportional to the degree of picture signal modulation; and means for affecting said light sensitive sheet by said light tracing along successive thin lines for producing the transmitter picture on said record sheet.

4. In a telepicture system, a transmitter comprising an electronic scanner including a cathode ray tube having a fluorescent screen, means for generating an electron beam and means for oscillating said beam in one direction at a predetermined frequency with one oscillation for each line of scanning across said fluorescent screen for generating a moving scanning point of light transversely of a picture film to be transmitted, means for moving said picture at right angles to the line of oscillation of said beam between successive oscillations thereof; a lens system interposed between said fluorescent screen and said picture film for focusing said moving point of light on said picture film; a photoelectric cell in operative relation with said scanner and said picture for generating telepicture signals of individual lines of scanning in accordance with the shading of said picture as said scanner scans the picture; means for generating an audio frequency carrier current which is a multiple of said oscillating frequency, means for producing a synchronizing impulse between successive lines of scanning, means for modulating said carrier current by said telepicture signals; a receiver comprising a corresponding electronic scanner including a cathode ray tube having a fluorescent screen, means for generating an electron beam, means responsive to said synchronizing impulses for oscillating said receiver beam in one direction at said predetermined rate with one oscillation corresponding to each of said lines of scanning for generating a moving point of light on the screen transversely of a light sensitive record sheet, and means for simultaneously moving said receiver beam at right angles to said oscillating direction in accordance with the picture modulations of the received signals for producing an individual stationary light tracing corresponding to successive lines of scanning of the picture, the tracing of each successive line being generated in substantially the same area of said receiver screen.

5. In a telepicture system, a transmitter comprising an electronic scanner including a cathode ray tube having a fluorescent screen, means for generating an electron beam and means for oscillating said beam in one direction at a predetermined frequency with one oscillation for each line of scanning across said fluorescent screen for generating a moving scanning point of light transversely of a picture film to be transmitted, means for moving said picture at right angles to the line of oscillation of said beam between successive oscillations thereof; a lens system interposed between said fluorescent screen and said picture film for focusing said moving point of light on said picture film; a photoelectric cell in operative relation with said scanner and said picture for generating telepicture signals of individual lines of scanning in accordance with the shading of said picture as said scanner scans the picture; means for generating an audio frequency carrier current which is a multiple of said oscillating frequency, means for producing a synchronizing impulse between successive lines of scanning, means for modulating said carrier current by said telepicture signals; a receiver comprising a corresponding electronic scanner including a cathode ray tube having a fluorescent screen, means for generating an electron beam, means responsive to said synchronizing impulses for oscillating said receiver beam along a single plane at said predetermined rate with one oscillation corresponding to each of said lines of scanning for generating a moving point of light on the screen transversely of a light sensitive record sheet, means for simultaneously moving said receiver beam at right angles to said plane in accordance with the picture modulations of the received signals for producing an individual stationary light tracing corresponding to successive lines of scanning of the picture, and means for affecting said light sensitive sheet by said light tracing along successive thin lines for reproducing the transmitter picture on said record sheet comprising a lens system interposed between said fluorescent screen and said sheet for focusing said light tracing

picture for generating telepicture signals of individual lines of scanning in accordance with the shading of said picture as said scanner scans the picture; means for generating an audio frequency carrier current which is a multiple of said oscillating frequency, means for producing a synchronizing impulse between successive lines of scanning, means for modulating said carrier current by said telepicture signals; a receiver comprising a corresponding electronic scanner including a cathode ray tube having a fluorescent screen, means for generating an electron beam, means responsive to said synchronizing impulses for oscillating said receiver beam along a single plane at said predetermined rate with one oscillation corresponding to each of said lines of scanning for generating a moving point of light on the screen transversely of a light sensitive record sheet, means for simultaneously moving said receiver beam at right angles to said plane in accordance with the picture modulations of the received signals for producing an individual stationary light tracing corresponding to successive lines of scanning of the picture; and means for affecting said light sensitive sheet by said light tracing along successive thin lines for reproducing the transmitter picture on said record sheet comprising a lens system interposed between said fluorescent screen and said sheet.

6. In a telepicture system, a transmitter comprising an electronic scanner including a cathode ray tube having a fluorescent screen, means for generating an electron beam and means for oscillating said beam in one direction at a predetermined frequency with one oscillation for each line of scanning across said fluorescent screen for generating a moving scanning point of light transversely of a picture film to be transmitted, means for moving said picture at right angles to the line of oscillation of said beam between successive oscillations thereof; a lens system interposed between said fluorescent screen and said picture film for focusing said moving point of light on said picture film; a photoelectric cell in operative relation with said scanner and said picture for generating telepicture signals of individual lines of scanning in accordance with the shading of said picture as said scanner scans the picture; means for generating an audio frequency carrier current which is a multiple of said oscillating frequency, means for producing a synchronizing impulse between successive lines of scanning, means for modulating said carrier current by said telepicture signals; a receiver comprising a corresponding electronic scanner including a cathode ray tube having a fluorescent screen, means for generating an electron beam, means responsive to said synchronizing impulses for oscillating said receiver beam along a single plane at said predetermined rate with one oscillation corresponding to each of said lines of scanning for generating a moving point of light on the screen transversely of a light sensitive record sheet, means for simultaneously moving said receiver beam at right angles to said plane in accordance with the picture modulations of the received signals for producing an individual stationary light tracing corresponding to successive lines of scanning of the picture, and means for affecting said light sensitive sheet by said light tracing along successive thin lines for reproducing the transmitter picture on said record sheet comprising a lens system interposed between said fluorescent screen and said sheet for focusing said light tracing

upon said sheet along a thin line, and means responsive to said synchronizing impulse for advancing said record sheet between successive lines of scanning.

- 5 7. In a telepicture system, a transmitter comprising an electronic scanner including a cathode ray tube having a fluorescent screen, means for generating an electron beam and means for oscillating said beam in one direction at a predetermined frequency with one oscillation for each line of scanning; across said fluorescent screen for generating a moving scanning point of light transversely of a picture film to be transmitted, means for moving said picture at right angles 10 to the line of oscillation of said beam between successive oscillations thereof; a lens system interposed between said fluorescent screen and said picture film for focusing said moving point of light on said picture film; a photoelectric cell in 15 operative relation with said scanner and said picture for generating telepicture signals of individual lines of scanning in accordance with the shading of said picture as said scanner scans the picture; means for generating an audio frequency 20 carrier current which is a multiple of said oscillating frequency, means for producing a synchronizing impulse between successive lines of scanning, means for modulating said carrier current by said telepicture signals; a receiver 25 comprising a corresponding electronic scanner including a cathode ray tube having a fluorescent screen, means for generating an electron beam, means responsive to said synchronizing impulses for oscillating said receiver beam along a single 30 plane at said predetermined rate with one oscillation corresponding to each of said lines of scanning for generating a moving point of light on the screen transversely of a light sensitive record sheet, means for simultaneously moving said 35 receiver beam at right angles to said plane in accordance with the picture modulations of the received signals for producing a stationary light tracing corresponding to individual lines of scanning of the picture, the tracing for each successive 40 line being generated in substantially the same area of said receiver screen; and means for affecting said light sensitive sheet by said light tracings along corresponding successive thin lines for reproducing the transmitter picture on 45 said record sheet comprising a lens system interposed between said fluorescent screen and said sheet for focusing said light tracing upon said sheet along a thin line, and means responsive to said synchronizing impulse for advancing said 50 record sheet between successive lines of scanning and a light filter interposed between said tracing and said record sheet for predetermining the action of said light tracing on said record sheet.
- 55 8. In a telepicture system, a receiver comprising an electronic scanner including a cathode ray tube having a fluorescent screen, means for generating an electron beam, means for oscillating said beam in one direction at a predetermined rate, with one oscillation corresponding to an individual line of scanning for generating a moving point of light on the screen transversely of a light sensitive record sheet, and means for simultaneously moving said receiver beam trans- 60 verse to said oscillating direction in accordance with received picture modulated carrier current whereby the width along any section of the image is proportional to the degree of picture signal modulation.
- 65 75 9. In a telepicture system, a receiver comprising an electronic scanner including a cathode ray tube having a fluorescent screen, means for oscillating said beam in one direction at a predetermined rate, with one oscillation corresponding to an individual line of scanning for generating a moving point of light on the screen transversely of a light sensitive record sheet, and means for simultaneously moving said receiver beam at right angles to said oscillating direction in accordance with received picture modulated carrier current whereby the width along any section of the image
- ing an electronic scanner including a cathode ray tube having a fluorescent screen, means for generating an electron beam, means for oscillating said beam in one direction at a predetermined rate, with one oscillation corresponding to an individual line of scanning for generating a moving point of light on the screen transversely of a light sensitive record sheet, and means for simultaneously moving said receiver beam at right angles to said oscillating direction in accordance with received picture modulated carrier current whereby the width along any section of the image is proportional to the degree of picture signal modulation; and means for affecting said light sensitive sheet by said successive light tracings along corresponding successive thin lines for reproducing the transmitter picture on said record sheet.
10. In a telepicture system, a receiver comprising an electronic scanner including a cathode ray tube having a fluorescent screen, means for generating an electron beam, means for oscillating said beam in one direction at a predetermined rate, with one oscillation corresponding to an individual line of scanning across said receiver fluorescent screen for generating a moving point of light on the screen transversely of a light sensitive record sheet, means for simultaneously moving said receiver beam at right angles to said oscillating direction in accordance with received picture modulated carrier current whereby the width along any section of the image is proportional to the degree of picture signal modulation; and means for affecting said light sensitive sheet by said light tracing along successive thin lines for reproducing the transmitter picture on said record sheet comprising a lens system interposed between said fluorescent screen and said sheet.
11. In a telepicture system, a receiver comprising an electronic scanner including a cathode ray tube having a fluorescent screen, means for generating an electron beam, means for oscillating said beam in one direction at a predetermined rate, with one oscillation corresponding to an individual line of scanning for generating a moving point of light on the screen transversely of a light sensitive record sheet, means for simultaneously moving said receiver beam at right angles to said oscillating direction in accordance with received picture modulated carrier current whereby the width along any section of the image is proportional to the degree of picture signal modulation; and means for affecting said light sensitive sheet by said light tracing along successive thin lines for reproducing the transmitter picture on said record sheet comprising a lens system interposed between said fluorescent screen and said sheet.
12. In a telepicture system, a receiver comprising an electronic scanner including a cathode ray tube having a fluorescent screen, means for generating an electron beam, means for oscillating said beam in one direction at a predetermined rate, with one oscillation corresponding to an individual line of scanning for generating a moving point of light on the screen transversely of a light sensitive record sheet, means for simultaneously moving said receiver beam at right angles to said oscillating direction in accordance with received picture modulated carrier current whereby the width along any section of the image

- is proportional to the degree of picture signal modulation; and means for affecting said light sensitive sheet by said light tracing along successive thin lines for reproducing the transmitter 5 picture on said record sheet comprising a lens system interposed between said fluorescent screen and said sheet for focusing said light tracing upon said sheet along a thin line, means for advancing said record sheet between successive lines of scanning, and a light filter interposed between said tracing and said record sheet for predetermining the action of said light tracing on said record sheet.
